Attest:

by

ARVID H. NERO

Arvid H. Nero Atty's.

UNITED STATES PATENT OFFICE.

ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC-LAMP SOCKET.

1,316,459.

Specification of Letters Patent. Patented Sept. 16, 1919.

Application filed April 7, 1917. Serial No. 160,446.

To all whom it may concern:

Be it known that I, ARVID H. NERO, a citizen of the United States of America, and residing at New Britain, in the county of 5 Hartford and State of Connecticut, have invented a certain new and useful Improvement in Electric-Lamp Sockets, of which the following is a specification.

My invention relates to electric lamp 10 sockets and the object of my invention is to provide a socket of simplified construction in which the assembly of the parts is readily accomplished by a simple operation with a minimum time consumption and the least 15 possible number of securing screws.

In the accompanying drawings,

Figure 1 is a side elevation of the body portion of a lamp socket, in which my invention is illustratively embodied;

20 Fig. 2 is a cross section on the line 2—2, Fig. 1;

Fig. 3 is a plan thereof;

Fig. 4 is a section on the line 4—4, Fig. 2; and

25 Fig. 5 is a section on the line 5—5, Fig. 1.

In socket construction it is customary to secure the various terminals, frame members, etc., to the insulating base by independent securing screws. This not only

30 necessitates a piercing of the porcelain at several points, thus weakening the already fragile material, but also consumes the time of operators in effecting the assembly of the parts and furthermore adds expense

35 through the use of numerous brass securing screws—an item of no small amount where sockets are made in large quantities.

By the present construction I have eliminated much of the weakness and most of 40 the unnecessary material by so arranging the parts that a single pair of screw bolts serves not only to unite the porcelain buttons which form the insulating body of the socket, but at the same time to secure in position all of the various metal parts used

45 in the construction.

The socket here shown comprises a pair of insulating buttons 10 and 11 recessed on their meeting faces to form a switch chamber 12, and grooved at 13 to afford wire channels leading to the binding screws 14 and 15. Within the switch chamber 12 is arranged a switch mechanism of the type shown in the Gates Patent No. 1,134,732,

mounted in a frame 16 having pairs of wings 55 17 and 18, which lie in appropriate slots 19 opening from the switch chamber and formed in adjacent faces of the buttons 10 and 11. A thumb key 20 projects from the side of the socket and operates the switch 60 mechanism, which need not be here described in detail, but comprises a rotary switch bar 21 which is adapted to bridge the space between the switch terminals 22 and 23 in the "on" position of the switch. The switch 65 terminal 22 extends from the switch chamber 12 into a channel 24 formed in the side of the button 11, and its inwardly offset end underlies the angled base 25 of the wire terminal 14 seated in a recess 26 in the outer 70 end of button 11. The other switch terminal 23 projects into side channel 27 and its offset end 28 forms the center contact of the socket. The wire terminal plate 29, carrying binding screw 15 is integral with a yoke 75 30 which overlies the base flange 31 of the screw shell 32 and forms the direct electrical connection between the binding screw 15 and the screw shell 32. The center contact strap 28, and the conductors 22 and 25 leading 80 from the wire terminal 14, all of which underlie the base flange 31 of the screw shell 32 are insulated from the latter by an insulating disk 33, notched at 34 to permit the strap 29 to pass inward therethrough. 85

The various parts are united by the screw bolts 35 and 36 which pass through both buttons 10 and 11 and take into the yoke 30. The apertures in strap 28 and conductors 24 and 25 through which the bolts 35 and 36 90 respectively pass, are of such size that ample clearance is afforded between the edges thereof and the bolts to prevent short-circuiting of the socket. When the bolts 34 and 35 are screwed tight, the yoke 30 is drawn down 95 firmly upon the metal parts interposed between it and the outer face of button 11 holding all of these parts rigidly in position. At the same time the switch frame is firmly clamped between the inner faces of 100 the buttons by reason of the configuration of the walls of the switch chamber 12. The switch mechanism itself is self-contained upon its frame as set forth in the patent above referred to, so that there is no necessity for securing screws to hold its parts in proper position.

Various modifications in details of con-

struction and arrangements of parts will readily occur to those skilled in the art to accomplish the objects hereby attained without departing however from what I claim 5 as my invention.

I claim:—

1. An electric lamp socket comprising a pair of insulating buttons recessed on their juxtaposed faces to form a switch chamber 10 with slots opening therefrom, a switch mechanism arranged in said chamber and having a frame with wings entering said slots to position the same in the chamber and prevent displacement thereof when the switch 15 is operated, said frame being clamped between the opposite faces of the insulating buttons, lamp terminals mounted at one end of said body, spaced wire terminals, switch terminals at opposite sides of the switch 20 chamber, and a single pair of screw bolts piercing said buttons in a direction parallel to the axis of the socket and serving as the sole means for securing all of said parts in assembled position.
2. An electric lamp socket, comprising an insulating body having at one end thereof a screw shell lamp terminal, conductors of opposite polarity lying between the base of said screw shell and the insulating body, insulation spacing said shell and conductors apart, and clamping screws piercing said 25 conductors but spaced therefrom and serving

to hold both said conductors and screw shell upon the insulating body.

3. An electric lamp socket, comprising an insulating body recessed to form a switch chamber, switch terminal straps passing from said switch chamber to the exterior of the socket body and angled over one end of the latter, a screw shell lamp contact of different polarity overlying said angled ends of the terminal straps, and spaced therefrom by insulation, together with screw bolts piercing the insulating body and screw shell terminal and serving to clamp said straps between the base of the screw shell terminal and socket body, substantially as described. 35 40 45

4. An electric lamp socket comprising a pair of buttons recessed on their juxtaposed faces to form a switch chamber, a switch mechanism having a frame freely inserted but clamped between said juxtaposed faces in the assembled fitting, switch operating mechanism mounted in said frame, lamp terminals mounted at one end of said body, spaced wire terminals, switch terminals within said switch chamber, and a single pair of screw bolts piercing said buttons in a plane parallel to the axis of the socket and serving as the sole means for securing all of said 50 55 60 parts in rigid, assembled position.

In testimony whereof I have signed my name to this specification.

ARVID H. NERO.
